UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

DESIGN FOR A HEATER FRAME.

Application filed May 29, 1924. Serial No. 8,744. Term of patent 14 years.

To all whom it may concern:

Be it known that I, JOSEPH ROY, a citizen of the United States, residing at Cleveland, in the county of Cuyahoga and State of Ohio, have invented a new, original, and ornamental Design for Heater Frames, of which the following is a specification, reference being had therein to the accompanying drawing.

In the accompanying drawings:

Figure 1 is a view in elevation of my new design for a heater frame.

Figure 2 is an end view of the heater frame.

I claim:

An ornamental design for a heater frame, as shown.

In testimony whereof, I hereunto affix my signature.

JOSEPH ROY.
